UNITED STATES PATENT OFFICE.

WILLIAM HENRY HALE, OF PITTSBURGH, PENNSYLVANIA, ASSIGNOR OF ONE-THIRD
TO HARRY L. FELSEB AND ONE-THIRD TO BOCCO G. FEMIA, BOTH OF PITTSBURGH,
PENNSYLVANIA.

1,104,623.

Specification of Letters Patent. Patented July 21, 1914.

Application filed August 5, 1913. Serial No. 768,152.

To all whom it may concern:

Be it known that I, WILLIAM HENRY HALE, a citizen of the United States of America, residing at Pittsburgh, in the county of Allegheny and State of Pennsylvania, have invented certain new and useful Improvements in Locks, of which the following is a specification, reference being had therein to the accompanying drawing.

This invention relates to locks, of permutation class, and has for its object to provide a lock, in a manner as hereinafter set forth, whereby certain releasing operations must be performed before the locking bolt can be released from a retaining device by rotation of the key and in so constructing the lock that one must understand the combination, as well as the manner of operation, before the locking bolt is released, thus rendering it impossible for unauthorized persons operating the lock.

Further objects of the invention are to provide a lock which is comparatively simple in its construction and arrangement, strong, durable, efficient and convenient in use, and comparatively inexpensive to manufacture.

With the foregoing and other objects in view the invention consists of the novel construction, combination and arrangement of parts as hereinafter more specifically described and illustrated in the accompanying drawing wherein is shown an embodiment of the invention, but it is to be understood that changes, variations and modifications can be resorted to which come within the scope of the claims hereunto appended.

In the drawings, wherein like numerals of reference denote corresponding parts throughout the several views:—Figure 1 is a front elevation of a lock in accordance with this invention. Fig. 2 is a front elevation, broken away, illustrating the stop member in one position. Fig. 3 is a view similar to Fig. 2, and showing the stop member in one position in full lines and in another position in dotted lines. Fig. 4 is a front elevation, with the outer plate of the casing removed, illustrating the latch members in engagement with the locking bolt, and Fig. 5 is a longitudinal sectional view of the lock.

Referring to the drawing in detail 1 denotes a rectangular casing having its outer end wall formed with a slot 2 and provided

with a spring 3, the latter being secured to the said outer end wall by a rivet 4.

The front wall of the casing 1 which is indicated by the reference character 5 is formed with an opening 6 into which extends an annular flange 7 carried by a circular revoluble disk 8 arranged against the outer face of the wall 5 and provided with a pair of outwardly projecting annular flanges 9, 10. Surrounding the disk 8 and fixed to the outer face of the front wall 5 is a circular plate 11 provided with graduations 12. The flange 7 is interiorly threaded and engaging with the threads of the flange and projecting inwardly from the flange 7 is a bearing sleeve 13. The flange 9 is provided with graduations, as at 14.

Arranged within the casing 1 and connected to the flange 7, as well as being rotatable upon the inner face of the front wall 5 is a barrel 15 having its inner edge formed with a notch or seat 16. The barrel 15 is shouldered in its periphery to provide in connection with the front wall 5 a pocket 17 into which extends a rib 18 projecting from the inner face of a barrel 19, which surrounds the barrel 15 and which normally is stationary. The barrel 19 is provided in its inner edge with a seat 20. The seat 16 is adapted to align with the seat 20 for a purpose which will be presently referred to. The barrel 19 has its periphery formed with a V-shaped lug 21 which is adapted to engage a pin 22 carried by the wall 5 whereby the movement of the barrel 19 is limited in one direction. The lug 21 is also adapted to engage a pin 23, spaced from the pin 22, carried by the wall 5. The pin 23 limits the movement of the barrel 19 in the opposite direction.

Arranged within the casing 1 and in proximity to the inner edges of the barrels 15, 19, is a partition or supporting plate 24, formed with a slot 25 and an opening 26. Pivotally mounted upon the plate 24 in proximity to the slot 25, through the medium of the pin 27 is a stop member 28, provided with a notch 29 adapted to normally register with the seat 20. The member 28, at one wall of the notch 29 is provided with a beveled lug 30 and is furthermore provided at the opposite side of the notch 29 with a beveled lug 31. Engaging with a pin 32 carried by the member 28 is a spring 33 which is fixed, as at 34. The function of

the spring 33 is to maintain the member 28 in such position, whereby the notch 29 will register with the seat 20, as shown in Figs. 2 and 3. The member 28 has its movement arrested in one direction, by a pin 35 which engages a shoulder 36. The pin 35 arrests the movement of the member 28 against the action of the spring 33.

The sleeve 13 has its inner end bifurcated 10 as at 37 and mounted in said sleeve 13, is what may be termed a rotatable key having a shank formed of two different diameters, the larger indicated at 38 and the smaller at 39. The inner end of the shank is provided with what may be termed a ward 40 and with a lug 41 which is arranged diametrically opposite the ward 40. The portion 38 of larger diameter of the shank of the key is mounted in the sleeve 13, and is 20 capable of being rotated in said sleeve as well as being longitudinally shiftable. The portion 38 of larger diameter is provided with a pair of oppositely disposed laterally extending projections 42 which extend 25 through the furcations at the inner end of the sleeve 13 and are adapted to engage a coiled compression spring 43 which is mounted upon the flange 7 and surrounds the sleeve 13. The function of the spring 43 is to normally maintain the ward 40 and lug 41 of the key clear of the plate 24. The reduced portion 39 of smaller diameter of the shank projects beyond the disk 8 and is provided with a finger piece 44 having an 30 annular flange 45 which is normally surrounded by the flange 9 and provided with 35 an indicating line 46.

The flange 10 is provided with an indicating line 47. The line 46 associates with 40 the graduations 14 and the line 47 associates with the graduations 12.

Pivoted upon a pin 48 is a pair of oppositely disposed latch members 49, 50. Each of the members 49, 50 is provided with an 45 inwardly extending nose 51, which is adapted to engage with a locking bolt 52 extended through the slot 2 and carried by a strike plate 53, the latter when the bolt 52 is engaged by the latch members 49, 50 bears 50 against the spring 3. When the bolt 52 is released from the latch members, the spring 3 forces the strike plate away from the casing, under such conditions the locking bolt 52 is carried therewith, so that the noses 55 51 of the latch members can not engage the bolt to hold it until the strike plate 53 is shifted toward the casing, to position the locking bolt 52 to be engaged by the latch members 49, 50. The latch members 49, 50 60 are maintained in operative position, that is the position which they assume to engage the locking bolt, by the ends of a spring 54, the said ends bearing against the latch members 49, 50 as clearly shown in Fig. 4. The 65 spring 54 is secured to the posts 55. The

latch members 49, 50 are opened, against the action of the spring 54 by a wedged-shaped releasing member 56, which is pivoted upon a pin 57. One end of the member 56 is cut away, as at 58 for engagement by the lug 21, whereby when the barrel 19 is rotated the lug 21 will engage the cut away portion 58 and rotate the member 56 upon its pivot 57 and as said member is rotated the ends of the members 49, 50 are shifted away 70 from each other, under such circumstances the noses 51 are swung clear of the head of the bolt 52. The movement of the lug 21 when rotating the member 56 is arrested by the pin 23.

The operation of the lock is as follows:— It will be assumed that the barrel 19 is in the position as shown in Fig. 3, with the seat 20 registering with the notch 29. The key is turned until the ward 40 engages the lug 30. At this point the key is pressed inwardly so as to clear the lug 30, after which it is positioned in the notch 29 between the lugs 30 and 31. The disk 8 is then turned to position the barrel 15 with its seat 16 in alinement with the seat 20. The key is then pulled outwardly against the action of the spring 43 and the ward 40 is positioned in the seats 16 and 20 and the lug 41 in one of the furcations 37, the ward 40 also extends 95 in one of the furcations 37. The key is then turned and the barrels 15 and 19 rotated, the rotating of the barrels causing the lug 21 to engage the member 56 rotate it and actuate the members 49, 50 to release the locking 100 bolt. When the key is released the spring 43 forces the ward 40 and the lug 41 clear of the plate 24 and the spring 54 returns the members 49, 50 to their normal position as shown in Fig. 4. Unless one is familiar with 105 the positioning of the key when it strikes the lug 30 of the stop member 28 the member will be rotated on its pivot so that the ward will clear the member 28 and the key completely rotated.

What I claim is:—

1. A lock comprising a lock bolt, a pair of latch members engaging with the bolt for locking it, a releasable member for and interposed between said latch members, a normally stationary barrel provided with a lug for actuating said releasing member when the barrel is rotated, a rotatable barrel, and a longitudinally shiftable and rotatable key provided with means for rotating 110 said barrels simultaneously to operate the releasing member.

2. A lock comprising a lock bolt, a pair of spring controlled pivoted latch members engaging with the bolt for locking it, a releasable means for and interposed between said latch members, a pair of rotatable barrels each provided with a seat, said seats normally out of alinement and adapted to aline when one of the barrels is rotated rela- 120 125 130

tively to the other, one of said barrels provided with means for operating the releasing member, and a longitudinally shiftable and rotatable key provided with means adapted 5 to engage in the registering seats for rotating said barrels simultaneously thereby causing the operation of the releasing member to free the bolt of the latch members.

3. A lock comprising a lock bolt, a pair of 10 spring controlled pivoted latch members enable means for and interposed between said gaging with the bolt for locking it, a releasing latch members, a pair of rotatable barrels each provided with a seat, said seats normally out of alinement and adapted to aline 15 when one of the barrels is rotated relatively to the other, one of said barrels provided

with means for operating the releasing member, a longitudinally shiftable and rotatable key provided with means adapted 20 to engage in the registering seats for rotating said barrels simultaneously thereby causing the operation of the releasing member to free the bolt of the latch members, and a spring controlled stop member constituting a positioning device for the means 25 carried by said element.

In testimony whereof I affix my signature in the presence of two witnesses.

WILLIAM HENRY HALE.
